CIGARETTE HOLDER

Fred F. Wenzel, South Bend, Ind.

Application July 22, 1936, Serial No. 91,974

1 Claim. (Cl. 131—51)

The invention relates to a cigarette holder and more especially to a safety holder for cigarettes.

The primary object of the invention is the provision of a holder of this character, wherein the cigarette when lighted and being smoked will be held in a manner to avoid the dropping of ashes upon the clothing of a smoker or on the floor as such ashes dropped from the cigarette will be trapped or caught by the holder.

Another object of the invention is the provision of a holder of this character, wherein, when the lighted cigarette is in the holder and the latter has been brought to rest, there is no liability of the cigarette contacting with furniture or other places where it has been brought to rest and thereby avoiding the burning, scorching or otherwise marring of such furniture or other support upon which the holder has been brought to rest.

A further object of the invention is the provision of a holder of this character which is extremely simple in construction, thoroughly reliable and effective in operation, permitting a cigarette or the like to be smoked in a convenient manner and with safety, strong, durable, and inexpensive to manufacture.

With these and other objects in view, the invention consists in the features of construction, combination and arrangement of parts as will be hereinafter more fully described, illustrated in the accompanying drawing, which discloses the preferred embodiment of the invention, and pointed out in the claim hereunto appended.

In the accompanying drawing:

Figure 1 is a top plan view of a holder constructed in accordance with the invention.

Figure 2 is a vertical longitudinal sectional view thereof.

Figure 3 is a view similar to Figure 2 showing the mouth piece separated and the latch of the holder engaged with a cigarette in the mouth piece for enabling the removal of such cigarette therefrom in a convenient manner.

Figure 4 is a sectional view on the line 4—4 of Figure 2 looking in the direction of the arrows.

Similar reference characters indicate corresponding parts throughout the several views in the drawing.

Referring to the drawing in detail, the cigarette holder comprises a mouth piece 5 having a central longitudinally extended smoke passage 6 therethrough, one end of the said mouth piece being reduced to provide an external annular seat 7 at this end. The reduced end portion of the mouth piece is provided with a socket 8 for accommodating a cigarette 9 when inserted therein so that the mouth piece will carry the cigarette for the smoking thereof in the conventional manner.

60 Removably fitted on the reduced end of the

mouth piece 5 is a tubular or barrel-like body 10 having the closed outer end 11 and the opposite open end 12, respectively. This open end 12 accommodates the reduced end of the mouth piece 5 so that the said open end of the barrel 10 will be accommodated in the annular seat 7 concentrically about the reduced end of said mouth piece.

The uppermost side of the barrel 10 has formed therein substantially rectangular shaped openings 13, these having gratings 14, respectively, to assure perfect draft when the cigarette 9 is being smoked on the carriage thereof in the mouth piece 5. The cigarette, when in the mouth piece 5, on the placing of the tube 10 on said mouth piece, projects into said tube longitudinally thereof. Thus it will be seen that the ashes dropping from the cigarette will be caught or trapped in the barrel 10 to avoid the falling of the ashes upon the clothing of a smoker or the floor.

Fixed to the grating 14 next to the open end 12 of the barrel 10 is a springy hook-like catch 15, its bill 16 being adapted to play through a suitable clearance in the barrel 10 to engage in the reduced end of the mouth piece 5 and in this manner the barrel 10 is detachably latched to the mouth piece. The bill 16, on separation of the barrel 10 from the mouth piece 5, can be brought into engagement with the cigarette 9, as is shown in Figure 3 of the drawing, so that the cigarette can be extracted from the socket 8 in the mouth piece 5 and in this manner ejected therefrom.

About the barrel 10 throughout the length thereof and at the closed end 11 is a fireproof covering 17 which is made fast to the barrel in any suitable manner so as to avoid heat radiating from the barrel 10 when the holder is at rest upon a piece of furniture or other support to avoid scorching or burning of the furniture or other support when the holder is at rest and the cigarette is lighted.

The covering 17 may be in the form of cork insulation or any other heat resisting material.

The holder by reason of its construction will serve as a home safety cigarette holder.

What is claimed is:

The combination of a mouth piece, a barrel closed at one end and open at the other end and detachably fitted with the mouth piece at its open end, the said barrel having openings, a heat and fire resisting covering on said barrel, and a latch carried by the barrel and engageable with the mouth piece for detachably securing the same together and also acting as a cigarette ejector by engaging the cigarette when within the holder on the separation of the barrel from the mouth piece.
